UNITED STATES PATENT OFFICE

SAMUEL S. CHILDS, OF BERNARDSVILLE, NEW JERSEY.

VEHICLE-WHEEL.

No. 845,054.

Specification of Letters Patent.

Patented Feb. 26, 1907.

Application filed March 20, 1906. Serial No. 306,959.

To all whom it may concern.

Be it known that I, SAMUEL S. CHILDS, a citizen of the United States, residing at Bernardsville, in the county of Somerset and State of New Jersey, have invented certain new and useful Improvements in Vehicle-Wheels; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

This invention relates to certain improvements in that class of vehicle-wheels which have spokes of spring material, the objects of the present improvements being to obtain greater durability and efficiency; to secure an elasticity which will permit a free movement of the hub and yet the transmission of uncomfortable vibrations, due to contact of parts of the wheel with the vehicle-body, will not be permitted; to prevent the production of noise due to the frequent contact of such parts, and to secure other advantages and results; some of which may be hereinafter referred to in connection with the description of the working parts.

The invention consists in the improved vehicle-wheel and in the arrangements and combinations of parts of the same, all substantially as will be hereinafter set forth, and finally embraced in the clauses of the claim.

Referring to the accompanying drawings, in which like letters of reference indicate corresponding parts in each of the several figures, Figure 1 is a side elevation of a vehicle-wheel of my improved construction in its preferred form. Fig. 2 is a section of the peripheral parts of the same, taken at line x of Fig. 1. Fig. 3 is a detail view of a certain tire-block adapted to be employed at the rim of said wheel. Fig. 4 is a side elevation of a wheel of modified construction which may be employed under some circumstances. Fig. 5 is a detail view of a portion of the tire-blocks thereof, and Fig. 6 is a sectional view taken at line y of Fig. 4, and Fig. 7 is an edge view of said wheel.

In said drawings, 10 indicates the hub of the wheel, 11 resilient spokes extending tangentially from said hub into engagement with the rim of the wheel, and 12 supplementary

spokes fastened to the main spokes 11 at 55 points about midway between the ends of said main spokes and extending from thence to the rim.

13 represents the annular side flanges or plates of the rim between which are clamped or fastened a series of segments 14, preferably to a large extent of non-metallic matter, which segments comprise the tire of the wheel. Said segments may be of wooden blocks, as indicated in Fig. 6; but in the preferred construction the said sections or blocks are subdivided in planes parallel with the major plane of the wheel, the subdivision being of pieces of leather 15, with metal plates 16 inserted between the groups or series.

The blocks, whether in single blocks, as in Figs. 4, 6, and 7, or composite blocks, as in Fig. 2, are in wedge-like segments abutting together at their extremities, the inner parts of their ends being recessed to receive the ends of the spring-spokes 11, which are somewhat enlarged at their extremities to enable bolt-holes to be formed therein without unduly weakening the said springs at their junction with the rim. The eyes or 75 enlargements 17, Fig. 1, closely fit the recesses of the blocks and to a certain extent serve as keys coöperating in retaining the blocks in serial position between the annular side plates or flanges 13 of the rim. The annular plates 13 are provided with inwardly-extending ribs 18, which enter grooves 19, Figs. 3 and 5, and thus to a large extent take the inward pressure of the tire-blocks and render the use of many bolts unnecessary.

When the segmental blocks are each composed of series or groups of leather pieces, as in Fig. 2, I prefer to interpose the metal plates 16 at suitable points between, dividing said pieces, for example, into three groups, more 85 or less, the metal and leather layers or pieces being preferably bolted together through holes 20, Fig. 3, so as to form a composite block, as before indicated, which is separable as a unit from the wheel and as a unitary 95 block may be inserted in its place and clamped independently by the bolts 21, which serve the double purpose of retaining said blocks in an annular series and of fastening the spokes to the rim.

The spokes 11 extend tangentially away from the hub, each making an egee curve to the rim or tire to which it is attached.

The hub 10 consists, preferably, of the tubular center piece 101, the flanges 102, blocks 103, and clamping-bolts 104, arranged in connection with the inner ends of the spoke-springs, as shown in Fig. 1. The center tube may be of one integral piece with the flanges 102 or not. The spring-spokes at their inner extremities have cross-heads or lateral extensions 112, which lie against the tube 101 under the blocks 103, and thus when said blocks 103 are bolted in place between the springs 11 and between the flanges 102 said blocks press oppositely against the radial extensions 111, wedging the same into rigid relation with the coöperating parts and with the hub and press down against the lateral extension 112, so that the spokes are firmly held from outward radial movement.

Having thus described the invention, what I claim as new is—

1. The improved wheel comprising a hub, a series of springs extending from the hub, said springs being enlarged at their outer ends and having bolt-holes therein, a series of segmental blocks abutting against one another to form a rim, and having recessed portions to receive the enlargements on the ends of the spokes, an annular rim-plate on each side of the rim, and bolts passing through the rim-plates and the bolt-holes in the spokes.

2. The improved vehicle-wheel comprising a hub, a series of spokes extending from the hub, the spokes having enlargements at their outer ends, the enlargements being provided with bolt-holes, a series of segmental blocks abutting end to end, the adjoining ends of the blocks being provided with recesses to receive the enlargements of the spokes to bind them together, annular rim-plates arranged on the opposed sides of the blocks to prevent

their lateral displacement, and bolts passing through the rim-plates and extending through the enlargements of the spokes.

3. The improved wheel comprising a hub, a series of spokes composed of spring material extending from said hub, the spokes having enlargements on their ends, the enlargements being provided with bolt-holes, segmental blocks having their ends abutting and forming a rim, and having recesses on adjoining edges to receive the enlargements of the spokes, annular rim-plates on opposed sides of the rim, the rim-plates having inwardly-extending ribs to engage the segmental blocks, and bolts passing through the rim-plates and through the bolt-holes on the spokes to secure the parts together.

4. The improved wheel comprising a hub, spring-spokes extending therefrom, the spokes having enlargements on their outer ends, the enlargements being provided with bolt-holes, segmental blocks composed of strips of material arranged longitudinally in the blocks, annular rims on opposed sides of the blocks, the annular rims having inwardly-extending ribs to engage the blocks, the ends of the blocks abutting and being recessed to receive the enlargements of the spokes, bolts passing through the rims and the bolt-holes in the spokes, and bolts passing through the strips to hold the strips together when the blocks are removed from the wheel.

In testimony that I claim the foregoing I have hereunto set my hand this 17th day of March, A. D. 1906.

SAMUEL S. CHILDS.
